UNITED STATES PATENT OFFICE.

WILLIAM COSBIE, OF SAN FRANCISCO, CALIFORNIA.

HORSE-COLLAR.

SPECIFICATION forming part of Letters Patent No. 399,841, dated March 19, 1889.

Application filed August 1, 1888. Serial No. 281,687. (No model.)

To all whom it may concern:

Be it known that I, WILLIAM COSBIE, of the city and county of San Francisco, State of California, have invented an Improvement in 5 Horse-Collars; and I hereby declare the following to be a full, clear, and exact description of the same.

My invention relates to the class of horse-collars, and especially to those known as 10 "short-straw" or "wool" collars, the peculiarity of which lies in the fact that the leather of the entire collar is sewed up completely, and is afterward stuffed instead of having the pieces sewed up over the stuffing, as is the 15 case with long-straw collars.

My invention refers to an improvement in the top of the collar, which said improvement consists in a cap-piece formed on one end of the back and adapted to cover the joint on 20 the top of the collar, and, in connection with said cap-piece, of an independent piece or strip which covers the straw just under the cap-piece and serves as a continuation of the back up to the joint.

25 The object of my invention is to provide, in a short-straw or wool collar, a suitable cap-piece for covering and protecting the joint at the top of the collar and forming a suitable guide or bearing for the hame-strap.

30 Referring to the accompanying drawings for a more complete explanation of my invention, the figure is a perspective view of the upper portion of my horse-collar, the cap-piece B being turned back to show the joint and the independent piece E below the cap-piece.

35 A is the back of the collar. It is usual in short-straw or wool collars to stitch the back clear up to each end, making the ends meet or nearly meet at the top of the collar, and 40 this joint is simply covered by a short strap. My improvement consists in making a cap-

piece, B, out of one end of the back A, said cap-piece being long enough and wide enough to completely cover the joint represented by C at the top of the collar. The cap-piece is 45 secured in place by a strap, D, and buckle d; but as this cap-piece must necessarily be loose for a certain distance down, so that it can be turned back, it will be seen that from the line at which it is loose up to the end of the 50 joint the stuffing would be exposed. In order to provide against this and to fully cover the stuffing, I insert a supplementary piece of leather, E, which is sewed in properly and splices the back, said supplementary piece 55 coming up fully to the joint at the top of the collar and lying just under the cap-piece. This construction gives to the top of the collar the same appearance as the usual short-straw or wool collar, and, in addition thereto, 60 it has the protecting cap-piece which covers the top of the joint, the usual second cap-piece, F, covering the bottom of the joint. The cap-piece fully protects the joint and affords a bearing for the hame-strap. 65

I am aware that in long-straw collars a top cap-piece is used, and I do not therefore claim such, broadly; but

What I do claim as new, and desire to secure by Letters Patent, is—

70 In a horse-collar, the back extended to form the cap-piece for covering and protecting the joint at the top of the collar, and an independent or separate piece inserted under the cap-piece and covering the straw or stuffing up to 75 the joint, substantially as herein described.

In witness whereof I have hereunto set my hand.

WILLIAM COSBIE.
